(57) **CLAIM**

The ornamental design for a liquid dispenser, as shown and described.

DESCRIPTION

FIG. 1 is a perspective view of a liquid dispenser illustrating the claim design.

FIG. 2 is a front view of the liquid dispenser shown in FIG. 1.

FIG. 3 is a rear view of the liquid dispenser shown in FIG. 1.

FIG. 4 is a left side view of the liquid dispenser shown in FIG. 1.

FIG. 5 is a right side view of the liquid dispenser shown in FIG. 1.

FIG. 6 is a top view of the liquid dispenser shown in FIG. 1.

FIG. 7 is a bottom view of the liquid dispenser shown in FIG. 1.

FIG. 8 is an exploded perspective view of the liquid dispenser shown in FIG. 1 with the bottom cover separated from the body of the liquid dispenser.

FIG. 9 is an exploded front view of the liquid dispenser shown in FIG. 8.

FIG. 10 is an exploded rear view of the liquid dispenser shown in FIG. 8.

FIG. 11 is an exploded left side view of the liquid dispenser shown in FIG. 8.

FIG. 12 is an exploded right side view of the liquid dispenser shown in FIG. 8.

FIG. 13 is a bottom view of the body of the liquid dispenser shown in FIG. 8 with the bottom cover removed from the body of the liquid dispenser shown separately for ease of illustration; and,

FIG. 14 is a top view of the bottom cover of the liquid dispenser shown in FIG. 8 with the bottom cover removed from the body of the liquid dispenser shown separately for ease of illustration.

The broken lines showing portions of the liquid dispenser form no part of the claimed design.

1 Claim, 14 Drawing Sheets
